UNITED STATES PATENT OFFICE.

AUGUSTUS H. HEISEY, OF PITTSBURG, PENNSYLVANIA.

DESIGN FOR GLASSWARE.

SPECIFICATION forming part of Design No. 12,372, dated July 26, 1881.

Application filed June 18, 1881. Term of patent 7 years.

To all whom it may concern:

Be it known that I, AUGUSTUS H. HEISEY, of Pittsburgh, in the county of Allegheny and State of Pennsylvania, have invented a new and useful Improvement in Designs for Glassware; and I do hereby declare the following to be a full, clear, and exact description thereof.

My improved design for glass dishes consists of a square, rectangular, or other polygonal shape, with the corners escutcheoned with frosted shell-patterns and the intermediate portion mainly plain or clear.

To illustrate I have shown this design in the accompanying drawings applied, in Figure 1, to a footed bowl, and in Fig. 2 to a salver.

In Fig. 1, *a* indicates the frosted or obscured shell-figure on the corners of the square or rectangular bowl, and *b* the intermediate clear part. The frost-work may be of any known character, the term being used to cover generally an obscured or partially-obscured surface, whether produced by a roughened mold, or by grinding, or by acid.

In Fig. 2, *a* also indicates the frosted shell-

figures on the corners of the rectangular salver, and *b* the clear part.

Between the shells *a* small ornamental figures, such as the lambrequins *c*, may be made, and, if desired, a central figure of appropriate design may be made at *d*. The design is carried out in foot and stem by shells *a'*, clear intermediate space *b'*, and ornaments *c'*.

This design is applicable to other articles of glassware besides those shown, and is handsome in appearance.

What I claim as my new and useful design for glassware is—

The polygonal shape with the corners escutcheoned with frosted shell-patterns and intermediate clear portion, substantially as described and shown.

In testimony whereof I have hereunto set my hand.

AUGUSTUS H. HEISEY.
